UNITED STATES PATENT OFFICE

BARTON H. COFFEY, OF ELIZABETH, NEW JERSEY, ASSIGNOR, BY MESNE ASSIGNMENTS, TO THE COOLING TOWER CO., INC., OF NEW YORK, N. Y., A CORPORATION OF NEW YORK.

COOLING-TOWER.

1,158,107.

Specification of Letters Patent. Patented Oct. 26, 1915.

Application filed June 8, 1914. Serial No. 843,706.

To all whom it may concern:

Be it known that I, BARTON H. COFFEY, citizen of the United States, and resident of Elizabeth, in the county of Union and State 5 of New Jersey, have invented certain new and useful Improvements in Cooling-Towers, of which the following is a specification.

My invention relates to improvements in the organization and combination of parts 10 in an atmospheric cooling tower whereby important gains in structural strength are obtained without increase of weight, and other advantages. I attain these objects by the arrangements of parts illustrated on the 15 accompanying drawings in which,

Figure 1 is a plan and Fig. 2 an elevation of the cooling tower as a whole, Fig. 3, a section on the line 1—1, Fig. 4, a detail of an intermediate vertical lattice girder post, and 20 Fig. 5 a detail of a corner post both shown in side elevation. Figs. 6 and 7 are details showing methods of fastening the louvers to the respective posts 1 and 2.

Similar figures refer to similar parts in 25 all views.

As a cooling tower is often erected on the roof of a building possessing a small margin of surplus strength it is important in addition to reducing costs, that the structure 30 should be as light as consistent with the dead load and wind stresses imposed upon it, and it must also be consistent with the building code in force at the site. In the majority of building codes of our first-class cities, columns are limited to a ratio of least radius of 35 gyration to unsupported length of approximately 120 irrespective of imposed load. This requirement necessitates an extremely heavy steel section often far in excess of load demands unless the unsupported 40 length of the column is small. Local stiffness must be provided to resist severe wind pressures to which cooling towers are especially subjected. A firm support must be 45 given the spray louvers 15 to resist wind stresses and ice loads in cold weather. The steel work must be fully exposed for painting and inspection in order to successfully combat corrosion to which cooling towers 50 are peculiarly liable. All of these requirements are accomplished by my improved construction without employing special members for the purpose.

In general the tower skeleton is of steel

sections comprising four corner posts 1, 55 Figs. 1, 2 and 5 joined horizontally at various levels by the members 3, the bracing being completed by the diagonal rods 4, thus forming a skeleton tower completely braced for horizontal thrust and in which the unsupported length of the columns as a whole 60 is fixed by the vertical spacing of the members 3. I call this the primary bracing. At intermediate points are located the lattice posts 2 secured to the horizontal members 3, 65 thus tying them in to the primary system of bracing.

The corner posts 1, Fig. 5, are braced individually only against vertical stress or weight, the member 12 transferring such 70 weight to the panel point 16, Figs. 2 and 5 of the primary system of bracing. The posts 2, Fig. 4 are completely braced individually forming a lattice girder with chords 7 and 8, horizontal members 5 and 75 inclined members 6 thus being able to receive both weight and horizontal thrust without buckling in the plane of the post, though weak in the other direction. In the planes of the horizontal members 3 and secured to them are the drip decks 14, Fig. 3 possessing great stiffness and strength horizontally in all directions, acting as horizontal solid girders and thus capable of transmitting horizontal wind stresses, received 80 from members 3 at intermediate points such as junctions with posts 2, back again to members 3 at their extremities and then into the panel points 16 of the primary system of bracing. 85

The inclined members 6 and 11 of the respective posts 2 and 1 support the louvers 15 which are formed of steel plate or tongue and groove boards of considerable width and possessing both girder and compressive 95 strength, and are thoroughly secured to the inclined members as shown at Figs. 6 and 7.

It follows then if the posts 2 tend to bend in the direction of the arrows A Figs. 1 and 2, between the horizontal planes of the members 3, such movement is communicated to the louvers 15 and transmitted by compression to the louvers at right angles thereto at the end of the tower, which in turn transfer it by girder strength to the end posts 2 in 100 the direction of the arrows B which lie in their plane of strength. Thus none of the posts 1 or 2 can buckle between the panel 105

points 16 without distorting other posts 2 in the plane of strength, and consequently the unsupported length of all posts can be taken at the pitch of the louvers, and light 5 sections used both in conformity with the code and with safety.

It is obvious from inspection of the various views that the steel frame is fully exposed for inspection and painting.

10 Having now described my improvement I claim:

1. In a cooling tower, side posts in the form of vertical latticed girders provided with inclined panel supporting members, in 15 structural combination with a louver system consisting of horizontal inclined plane members possessing considerable tensile compression and girder strength, and rigid fastenings connecting the inclined members with 20 the louver system, thereby making the com-

bination an integral whole; substantially as and for the purpose described.

2. In a cooling tower a completely braced frame or skeleton, vertical latticed girders, and a louver system consisting of plane 25 members possessing considerable tensile compression and girder strength rigidly joining the girders with the frame at and between panel points; whereby a structure is created braced both locally and as a whole 30 substantially as and for the purpose described.

Signed at 50 Broad St. New York city in the county of New York and State of New York this sixth day of June A. D. 1914.

BARTON H. COFFEY.
